Howard R. Hughes, Inventor

By his Attorney Jesse R. Stone

UNITED STATES PATENT OFFICE.

HOWARD R. HUGHES, OF HOUSTON, TEXAS.

ROTARY BORING-DRILL.

1,327,913.

Specification of Letters Patent. Patented Jan. 13, 1920.

Application filed May 19, 1919. Serial No. 297,979.

To all whom it may concern:

Be it known that I, HOWARD R. HUGHES, a citizen of the United States, residing at Houston, Harris county, Texas, have invented 5 a certain new and useful Improvement in Rotary Boring-Drills, of which the following is a full, clear, and exact description, such as will enable others skilled in the art to which it appertains to make and use the 10 same.

My invention relates to an improvement in rotary boring drills for use in drilling earth or rock in oil, water, or gas wells, or the like. It has special application to earth 15 boring drills of the roller type, in which the cutting or drilling operation is performed by means of rotary cutters adapted to roll upon the bottom of the hole and disintegrate the material which is adapted to be flushed 20 away by means of streams of water forced downwardly through the hollow drill stem and the head of the bit. This particular form of roller bit is called the cross roller type from the fact that it has two side cutters 25 for drilling the outer periphery of the hole and a central cross roller for cutting the center of the bottom of the hole.

An object of my invention is to provide a 30 drill bit of the character described in which the cutters are mounted in a most efficient manner for the drilling operation.

Another object is to provide a drill of the cross roller type in which the cutters are especially mounted to act upon the sides and 35 bottom of the hole with the greatest possible freedom, and in which the mounting shall be of reinforced construction to prevent breaking or mutilation thereof. Other objects and advantages will more clearly appear 40 in the description which follows.

Referring to the drawings forming a part 45 of this specification, and in which like characters of reference are applied to like parts throughout the several views, Figure 1 is a side view partly in elevation and partly in central longitudinal section showing the preferred form of my invention; Fig. 2 is a similar view taken at right angles to the view shown in Fig. 1; Fig. 3 is a bottom 50 plan view of the preferred embodiment; and Fig. 4 is a broken view of the head of my improved tool, showing a modified mounting of the cross roller cutters.

My invention is an improvement on the

type of bit shown in my previous Patent No. 55 1,174,576, patented March 7, 1916. It comprises an approximately cylindrical shaped head 1, having an upper threaded shank 2 for attachment to a rotary drill stem, not shown. At the upper end of the shank 2 is 60 a threaded nipple 3 of small diameter to which a lubricant container is adapted to be attached. The lower face of the head is provided with an approximately V-shaped slot 4 to provide a housing for two sets of 65 cross roller cutters 5. These cutters are mounted upon shafts 6 supported at the center of the bit in a transverse web 7. This web not only furnishes a support for the cutter shafts but also provides a reinforcing 70 means transversely of the V-shaped slot 4 to materially strengthen the head of the bit. This web is an important feature of my invention, as will more clearly appear. The outer ends of the cutter shafts 6 are 75 supported in downwardly projecting arms 8 from the head, these arms serving to partially close the end of the V-shaped slots 4, in which the cutters are mounted. The cutter shafts 6 are of large diameter at the 80 outer end to accommodate a cutter 5^a of slightly larger diameter than the other cross roller cutters, and is reduced somewhat in diameter toward the center of the head to accommodate a plurality of somewhat 85 smaller cutters 5^b. The shaft in my improved embodiment is inclined somewhat upwardly toward the center of the head and is still further reduced in diameter at 9 and threaded for engagement with the central web 7 of the head. The shaft is 90 retained in position partly by the threaded engagement 9 and also by means of a locking pin 10 at the outer end of the shaft, this pin being set in the side of the supporting member 8 at right angles to the shaft and fitting within an annular groove 11 in the periphery of the shaft. It will be noted that the threading of the shaft 6 into engagement with the central web 7 not only assists in 100 retaining the shaft in position but also materially strengthens the head by preventing any tendency of the outer support 8 to be spread outwardly by the force of the cutting action. The cutter shaft for the cross rollers may be horizontal instead of inclined upwardly, as shown in Figs. 2 and 3, and obtain a still further strengthening of the 105

head. This form of cutter shaft is shown in Fig. 4. The shaft 6' is mounted at each end in the supporting arm 8 and is further supported at its central point in the central 5 web 7, as described in the previous modification. The cutters used in this modification are identical with those shown in Fig. 2.

The side cutters 12 are mounted on the sides of the head at the lower end thereof. 10 These cutters are disk-shaped, having an outer cylindrical cutting periphery 13 with the outer edge of the cutting face beveled to provide cutting teeth 14 in such position as to act upon the side of the hole being 15 drilled. The inner edge of the cutting disk is also toothed, as shown at 15, to accommodate a slight cutting action toward the center of the bit. These two side cutters are mounted upon pins 16 which are made integral with the outer side walls 17 of the V-shaped housing at the lower end of the head. Said pins 16 are threaded and are reduced in diameter at the outer end at 18 to accommodate a locking nut 19. 20 Threaded upon the pins 16 are bushings 20, these bushings being slightly frusto-conical on their outer periphery, as shown in Fig. 1. The cutters 12 are provided with a frusto-conical inner bearing surface 21 25 adapted to fit against the bushing 20. The inner faces of the cutters 12 bear against anti-friction washers 22 of ordinary construction. It will be noted that in assembling this cutter the bushing 20 will be inserted within the cutter and in this position will be threaded upon the cutter pin 16. The locking nut 19 will then be threaded upon the cutter end 18 of the pin, thereby serving to prevent the removal of the bushing and cutter. This form of mounting for the cutter is especially adapted for the purpose, in that the upward and outward thrust of the cutting action will be received against the frusto-conical surface of 40 the bushing in such manner as to most efficiently withstand the pressure and to provide a bearing surface such that the cutter will be freely rotatable at all times. The side cutters 12 are so mounted as to give as 45 free rotation thereof as possible, and for this reason are not housed in the head but are left as open as possible on the sides for free drilling action, the head being recessed slightly at 23 to allow for the inward inclination of the cutters necessary in this 50 form of bit.

The cutters are lubricated by means of lubricant passing downward from the lubricant container through the central channel 60 24. This channel has two laterally branching ducts 25 leading to the center of the cutter shafts 16 and through lateral ducts 26 to the bearing surface between the cutter and the bushing. The central channel 24 65 leads downward through the central web

7 to the shaft 6, and through central ducts 27 therein to the bearing surfaces of the cutters.

Flushing water for carrying away the material disintegrated by the bit is supplied 70 through vertical channels 28 leading from the upper shank of the bit downwardly to the V-shaped recesses 4. These channels are 4 in number, as shown particularly in Fig. 3, there being 2 of these channels in the 75 housing at each side of the transverse web 7. A large supply of the flushing water is thereby obtained so that the bottom of the hole is washed constantly clean of cuttings, it being thereby unnecessary to supply flushing water directly upon the side cutters 12. 80

This form of bit is particularly strong in construction due to the manner in which the cutters are mounted in the head. The strengthening of the two side walls 17 by 85 means of a transverse web prevents any spreading of the lower faces upon which the cutters are mounted and also provides a central support for the cross roller. The forming of the side-cutter pins 16 integral with 90 the head gives an especially strong support, and the frusto-conical bushing 20 very effectively takes up the thrust of the cutting action of these cutters. Cutters 5 upon the cross roller shaft 6 are stepped downwardly 95 toward the center of the bit so as to drill a hole with a slightly convex or conical shaped bottom. This will act to prevent a too pronounced whipping or wobbling action of the bit in the hole and will serve to center the 100 bit so that a straight hole may be more readily drilled.

It also allows for a strengthening of the walls 17, upon which the side cutters 12 are mounted, by making it possible to thicken 105 the walls toward the center of the bit where the cutters are of smaller diameter. The purpose of centering the bit in the hole is further served in the preferred embodiment of my bit by inclining the cutter shafts 6 110 slightly upwardly toward the center. This makes it possible to thicken the walls of the bit somewhat at the center portion and acts still more efficiently to center the bit.

The mounting of the cutters in uninclosed position on the side of the bit not only allows a free cutting action of the cutters but allows the head to be made somewhat stronger due to the fact that the cutter may be set outwardly far enough to provide a 120 strong inner supporting wall 17 upon which the cutter is mounted. It is obvious that if it were necessary to extend the wall of the head downwardly to support the outer end of the cutter pin 16, so as to provide a slot 125 or housing for the outer cutter, it would also be necessary that the outer cutter be of decreased thickness, and that it also be set farther inwardly toward the center of the head so that the supporting wall at the 130

outer face might extend downwardly to engage the cutter end of the cutter pin. This, as would be obvious, would make necessary a cutter which would easily break in ordinary operation.

Having thus described my invention, the further objects and advantages of which will be obvious, what I claim as new and desire to protect by Letters Patent is:

- 10 1. In a rotary boring drill, a head, two sets of cylindrical cross roller cutters so positioned as to drill a hole with a conical shaped bottom, two side cutters mounted on pins projecting outwardly from the sides of the head, said cutters being retained in position by frusto-conical shaped bushings threaded on pins integral with said head, and locking means to hold said bushings on said pins.
- 15 2. In a rotary boring drill, a head, two sets of cross roller cutters thereon, two laterally projecting pins integral with the

sides of said head, frusto-conical bushings threaded on said pins, the larger ends of said bushings being toward the outer ends 25 of said pins, and cutters mounted on said bushings and retained in position thereby.

3. In a rotary boring drill, a head, an approximately V-shaped housing in the lower end thereof, a transverse web midway 30 of said housing adapted to divide said housing into two chambers to strengthen the walls of said housing, inclined cutter shafts in said chamber supported at one end in said web, cylindrical cutters on said shafts, the 35 cutters being of unequal diameter and arranged with the smaller cutters at the center of the head, two opposite cutters on the outer face of the head and means to discharge flushing water into said housing. 40

In testimony whereof, I hereunto affix my signature this the 15th day of May, A. D. 1919.

HOWARD R. HUGHES.
